UNITED STATES PATENT OFFICE.

ANDREW NAGY, OF SOUTH BEND, INDIANA.

WINDOW GUARD.

Application filed June 18, 1925. Serial No. 37,954.

This invention relates to new and useful improvements in window guards.

The primary object of the invention is the provision of a guard for a window which includes a multiplicity of bars carried by supporting, flexible members, which with the said bars, are capable of being wound upon a carrier within the window frame when not in use.

10 A further object of the invention is to provide means for causing the bars, when not wound upon the carrier, to be arranged transversely of the window and to be held in such position for preventing the unauthorized entrance of a person through the window.

Other objects and advantages of the invention will be apparent during the course of the following description.

20 In the accompanying drawings forming a part of the specification, and in which like numerals are employed to designate like parts throughout the same,

Figure 1 is a front elevational view of the device embodying this invention when viewed from the inner side of the window, certain face boards of the window frame being removed for more clearly illustrating the window guard operating mechanism,

30 Figure 2 is a vertical sectional view taken on line II—II of Figure 1,

Figure 3 is a vertical sectional view similar to Figure 2 but shows the window guard wound upon a carrier located within the window frame,

35 Figure 4 is a vertical sectional view taken upon line IV—IV of Figure 1,

Figure 5 is a horizontal sectional view taken upon line V—V of Figure 1,

40 Figure 6 is a horizontal sectional view taken upon line VI—VI of Figure 1,

Figure 7 is a fragmentary enlarged horizontal sectional view of one side of the window frame, and shows the construction of the upper and lower window sashes and the shape of the window guard guiding strips carried by the vertical sides of the window frame, and

45 Figure 8 is a detail perspective view of a fragmentary portion of one of the flexible supporting members to which the bars are fastened at their ends.

In the drawings, wherein for the purpose of illustration is shown the preferred embodiment of this invention, the numeral 5 designates the bottom horizontal board of a

window frame which has extending vertically therefrom the inner side boards 6 and 7 which have connected to their longitudinal edges the inner and outer facing boards 8 and 9 respectively. These inner and outer facing boards have their free longitudinal edges connected to the finishing boards 10 and 11 which extend in parallelism with the boards 6 and 7 respectively.

50 The boards 6 and 7 are provided on their inner vertical faces with window sash guiding strips 12 between which the upper and lower sash frames 13 slide. These sash frames are provided with the usual sash cords 14 and sash weights 15 which function in a well known manner for counter-balancing the window sashes. The sash frames 13 are best illustrated in Figure 7 as being formed with rabbeted inner edges 16 which 55 are intended to receive the window pane carrying frames 17 which have rabbeted edges 18 in which the window panes 19 are held by the cement or other similar substance 20. These window pane carrying frames are hinged at 21 to the sash frames 13 and may be moved or swung horizontally inwardly, as illustrated in dotted lines in Figures 6 and 7, for permitting the panes to be easily cleaned.

60 The vertical inner boards 6 and 7 of the window frame have connected thereto the horizontal board 22 which is arranged in spaced relation to the top finishing board 23 and with the inner and outer facing boards 24 and 25 form a compartment 26 in the window frame. The board 22 is provided with a longitudinally extending slot 27 which is formed with its longitudinal sides converging downwardly for forming a 65 tapering guide-way.

Connected to the vertical side boards 6 and 7 and depending truly vertically from the opposite ends of the slot 27 are the channel-shaped guiding strips 28 which engage the bottom board 5 at their lower ends and register with a slot 29 formed in the board 5.

70 Depending from the board 5 is an elongated chamber 30 which communicates with the said slot 29.

75 Journalized in the upper end portion of the boards 6 and 7 is a horizontal rod 31 which has a bevel gear 32 fastened to one end and meshing with a bevel gear 33 carried by the upper end of the vertical shaft 34 which is journalized in the brackets 35 and 36 fastened to the outer face of the side board 6. The

lower end portion of this shaft 34 has fastened thereto a bevel gear 37 which meshes with a bevel gear 38 carried by a stub shaft 39 which is journaled in a bearing 40 and has the crank handle 41 fastened to the outer end thereof. This structure is clearly illustrated in several of the figures and it will be understood by an inspection of the same that rotation of the crank handle in 10 opposite directions will cause the rod 31 to rotate in opposite directions.

Fastened at their upper ends to the rod 31 at points arranged in close proximity to the side boards 6 and 7 are flexible supporting 15 members 42, which in this showing are in the form of link chains. Figure 8 shows one of these chains 42 with the bifurcated end 43 of a guard bar 44 fastened to one link thereof. It is to be understood that a multiplicity of these bars 44 are fastened at their 20 opposite ends to the flexible supporting chains 42 and are arranged in suitable spaced relation to each other.

In Figures 1 and 2 the flexible supporting 25 chains and the guard bars are shown arranged to protect the entire length of the window opening to the window frame with the ends of the bars and the flexible supports received within these channel-shaped 30 guiding strips 28. In Figure 3 these flexible supports and the bars are shown as being wound upon the rod 31 within the compartment 26, the lowest bar 44, however, still being arranged with its ends received within 35 the guiding strips 28 and prevented from being withdrawn from these strips by the laterally projecting stop pins 45. These pins are employed for preventing the last bar 44 and the ends of the flexible supporting 40 chains 42 from being drawn into the compartment 26.

It will be noted that Figures 2 and 3 show several links of the supporting chains 42 depending from the bottom bar 44. It is to 45 be understood that when the flexible supporting chains and the bars are entirely unwound from the rod 31, these depending end links, which will be given the separate reference numeral 46, are received within 50 the chamber 30. The spring pressed pins 47 are employed for being passed through one of these end links 46 for preventing an unauthorized person from raising the bars 44.

It is now believed that the manner of construction and method of operation of this 55 window guard will be clearly understood from the above detailed description. It is further to be understood that the form of this invention herewith shown and described is to be taken as the preferred example of 60 the same, and that various changes in the shape, size, and arrangement of parts may be resorted to without departing from the spirit of the invention or the scope of the 65 subjoined claims.

Having thus described the invention, I 65 claim:

1. In a window guard of the character described, a window frame comprising a head compartment having a bottom wall, there 70 being a longitudinally extending slot in said bottom wall, a chamber beneath the sill of the frame, a flexible rolling grating supported in the compartment and trailed through the bottom wall slot, said grating 75 comprising spaced side chains and tubular rods bifurcated at their ends to receive a link of the adjacent chain, means for anchoring the ends of the rods to the chains, radial pins carried by the outermost rod to engage 80 the walls of the slot to prevent complete housing of the grating in the compartment, the outer end of the grating when extended being received in the channel beneath the sill and means for retaining the ends of the 85 grating in the channel.

2. In a window guard of the character described, a flexible rolling grating comprising spaced side chains and tubular rods bifurcated at their ends to receive a link of the 90 adjacent chain and means for anchoring the ends of the rods to the chains.

3. In a window guard of the character described, a flexible rolling grating comprising spaced side chains and tubular rods bifurcated at their ends to receive a link of the 95 adjacent chain, means for anchoring the ends of the rods to the chains, each chain link comprising a flat rectangular frame and a hook engaged with a frame bar of the 100 adjacent link with the flat rectangular portion of the link received in the bifurcated rod ends.

In testimony whereof I affix my signature.

ANDREW NAGY.
